[57] CLAIM

The ornamental design for a molding, as show and described.

DESCRIPTION

FIG. 1 is a perspective view of the molding;
FIG. 2 is a top view thereof;
FIG. 3 is a front view thereof;
FIG. 4 is a side-edge view thereof; the other side being identical thereto;
FIG. 5 is a bottom view thereof; and,
FIG. 6 is a rear view thereof.
The molding has been broken away in the center to show indeterminate length.
